UNITED STATES PATENT OFFICE.

HARLAND W. CARDWELL, OF TEXARKANA, ARKANSAS.

DITCH-FILLING MACHINE.

1,244,290.

Specification of Letters Patent. Patented Oct. 23, 1917.

Application filed October 30, 1916. Serial No. 128,503.

To all whom it may concern:

Be it known that I, HARLAND W. CARDWELL, a citizen of the United States, residing at Texarkana, in the county of Miller and State of Arkansas, have invented certain new and useful Improvements in Ditch-Filling Machines; and I do declare the following to be a full, clear, and exact description of the invention, such as will enable others skilled in the art to which it appertains to make and use the same.

My invention is an improved machine designed primarily for use in filling ditches and other excavations with the same earth which has been removed therefrom, but it is to be understood that the machine may be employed wherever applicable.

The principal object of the invention is to provide a comparatively simple yet highly efficient and durable machine of the class described having a number of adjustments for permitting it to operate advantageously under various conditions.

With this general object in view, the invention resides in certain novel features of construction and in unique combinations of parts to be hereinafter fully described and claimed, the descriptive matter being supplemented by the accompanying drawings which constitute a part of this application and in which:

Figure 1 is a top plan view of the improved machine with the derrick frame in horizontal section;

Fig. 2 is a vertical transverse section on the plane of the line 2—2 of Fig. 1;

Fig. 3 is a side elevation;

Figs. 4 and 5 are detail vertical transverse sections taken respectively on the planes of the lines 4—4 and 5—5 of Fig. 1;

Fig. 6 is a transverse section taken approximately on the plane of the line 6—6 of Fig. 1 with parts broken away;

Fig. 7 is a top plan view of the parts shown in Fig. 6 with the derrick frame in horizontal section;

Fig. 8 is a vertical section on the plane of the line 8—8 of Fig. 6;

Fig. 9 is a detail horizontal section on the plane of the line 9—9 of Fig. 6, showing the pivotal connection between the relatively fixed and movable tracks; and

Fig. 10 is a detail longitudinal section taken substantially on the plane indicated by the line 10—10 of Fig. 1, showing more

particularly certain features of the driving means.

In specifically describing the structure shown in the drawings above briefly described, similar characters will be employed to designate corresponding parts throughout the several views and reference will be herein made to the numerous elements by their respective indices. To this end, the numeral 1 designates a suitable main frame supported at its front ends by dirigible wheels 2 and in its rear ends by traction wheels 3. Depending from one of the side bars 4 of frame 1 is a pair of hangers 5 to which a pair of parallel relatively fixed T-iron tracks 6 are pivoted at one end, the other ends of said tracks having bearings 7 (see Fig. 9) through which horizontal journals or pintles 8 pass, such journals extending outwardly from a pair of attaching plates 9 which are secured to the inner ends of a pair of relatively movable T-iron tracks 10 which are aligned with the tracks 6. The tracks 10 are preferably reinforced by plates 11 riveted or otherwise secured thereto and said tracks are preferably formed of sections secured together by plates 12 as shown clearly in Figs. 1, 6 and 7.

The journals 8 pass through bearings 13 on the lower ends of a pair of upright hangers 14 which slide through bearing blocks 15 secured between the lower ends of upstanding plates 16, said plates being in turn secured to transverse sleepers 17 on the frame 1, said sleepers also having openings 90 through which the hangers 14 pass. The upper ends of the bars 14 extend above the sleepers 17 and are formed with openings 18 through which stop pins 19 are inserted. It will thus be evident that by adjusting the position of the pins 19 the bars 14 may be either held in raised or lowered position to properly adjust the tracks 6 to meet the character of the work being performed.

A carriage 20 is provided with upper rollers 21 and 22 and with lower rollers 23 and 24 which are adapted to engage the horizontal flanges of the tracks 6 and 10, the rollers 21 being disposed directly above 23 while the axes of the rollers 22 are offset 105 horizontally from those of the rollers 24. This offset relation prevents binding of the outer rollers as they travel from one pair of tracks to the other when the outer tracks 10 are disposed in an inclined position as de- 110

picted in Fig. 2. It is unnecessary to offset the inner rollers 21 and 23 in the manner in which rollers 22 and 24 are offset since said inner rollers may be spaced vertically a sufficient distance to prevent them from binding. The outer rollers, however, cannot be so spaced or the carriage would pull upwardly and strike the cross tie bars of the tracks 10 when said carriage is being brought inwardly. This would be caused by the fact that the entire weight of the tracks rests on the carriage and scraper during inward movement of these parts.

For varying the inclination of said tracks, a suitable yoke 25 is connected with the outer end thereof and carries a pulley 26 around which a cable 27 is trained, one end of said cable being anchored at 28 to the upper end of a suitable derrick frame 29 which rises from the rear end of the frame 1 immediately above the tracks 6. The other end of cable 27 is trained over a pulley 30 mounted on said derrick frame and is wound on a drum 31 whose mounting and driving means will be hereinafter described. It will be understood however, that winding of the cable 27 on the drum 31 will raise the outer end of the tracks 10 whereas unwinding of said cable will permit said tracks to lower by gravity.

The carriage 20 includes a pair of parallel J-shaped drawbars 32 connected by transverse bars 33 and suitably braced as indicated at 34, bearings 35 being mounted on said drawbars for rotatably supporting the shafts 36 to the numerous rollers. The curved downwardly directed ends of the bars 32 have secured thereto an earth scraping blade 37 which is braced to the carriage 20 by means of rods 38. A pair of sprocket chains 39 are secured at their opposite ends to the carriage 20, said chains being trained around sprockets on a shaft 40 extending between the front ends of the tracks 10, and around additional sprockets on a shaft 41 above the rear ends of the tracks 6. The upper reaches of the chains 39 pass under a roller 42 which is mounted between the innermost plates 16, and over another roller 43 carried by suitable brackets 44 which rise from the inner ends of tracks 10. Other rollers 45 support thereon the upper reaches of the chains 39, said rollers being mounted above the outer ends of the tracks 10, which ends are here connected by a pair of rigid transverse bars 46. By means to be herein-after explained, the chains 39 may be driven in either direction, thereby permitting the scraper 37 to be moved outwardly away from a ditch or the like D to be filled and then be pulled inwardly to draw a quantity of earth into said ditch, (see Fig. 2.) During its inward movement, the carriage will travel from the tracks 10 onto the tracks 6 and 65 may thus move inwardly the necessary

amount to deposit the load of the scraper 37 where needed. As the pile of earth is gradually thrown into the ditch, the tracks 10 will be lowered as will be readily understood. The tracks 10 are raised and lowered at the outward and inward movement of the scraper 37.

A line shaft 50 extends longitudinally of the frame 1 and is driven by suitable gearing 51 from an engine 52 mounted on the front end of said frame, it being upon this shaft that the drum 31 is loosely mounted. A combined clutch and brake 53 is provided for controlling the movement of said drum, this device serving when in one position to 80 rotate the drum from the shaft to wind the cable 27 for the purpose of raising the tracks 10 but when in its other position said device locks the drum against movement. A pair of clutch members 54 and 55 are arranged on the rear end of shaft 50 and are provided with a single control lever 56, the member 54 being connected with a second longitudinal shaft 57 by means of a sprocket chain 58, while gearing 59 connects the member 55 with said shaft 57. By means of a sprocket chain 60, the shaft 57 drives the shaft 41, said sprocket passing around an idler 61 as shown clearly in Fig. 6. By operating the lever 56 to throw the clutch member 54 into operation, the sprocket chain 58 will drive shaft 57 in the direction in which shaft 50 is rotated, but when lever 56 is thrown to its opposed position, clutch member 55 is thrown into use with the result that the two gears 59 will turn shaft 57 in the reverse direction. By the single lever 56, therefore, the direction of movement of the shaft 41 is under control and thus the chains 39 may be driven in either direction 105 at will to move carriage 20 inwardly and outwardly along the tracks.

Two clutch members 65 and 66 are loosely mounted on the shaft 50 for coöperation one at a time with another clutch member 67 110 which is keyed to said shaft and may be shifted thereon at will by a lever 68. Member 65 is connected with a longitudinal shaft 69 by means of a sprocket chain 70 while a gear 71 connects member 66 with said shaft. 115 It will thus be seen that by throwing the member 67 into engagement with one or the other of the members 65, 66, the shaft 69 may be rotated in either direction. A sprocket chain 72 transmits motion from 120 shafts 69 to a longitudinal shaft 73 disposed in a plane below said shaft 69, and this shaft 73 drives a second longitudinal shaft 74 through the instrumentality of a sprocket chain 75. The shaft 74 has thereon a bevel 125 gear 76 meshing with a similar gear 77 on a transverse shaft 78, this last named shaft being operatively connected by a sprocket chain 79 with a differential 80 on an additional transverse shaft 81. The ends of 130

shaft 81 transmit motion to the driving wheels 3 by sprocket chains 82 or other suitable connections.

In operation, the machine will straddle the ditch D as shown in Fig. 2 when it is to be used for filling such a ditch, and the tracks 6 and 10 will be adjusted to the proper heights by means of the hanger bars 14 and the cable 27. These adjustments having been made, the operator will control the lever 56 to drive shaft 57 first in one direction and then in the other to respectively move the carriage 20 outwardly and then inwardly, the blade 37 of said carriage moving a quantity of earth into the ditch as it travels inwardly. As it is necessary to move the entire machine forwardly or rearwardly as occasion may demand, the lever 68 will be operated to throw the clutch member 67 into engagement with 65 or 66 according to the direction of travel. By operating the machine in this manner, a great deal of work can be accomplished with little manual labor and at a small expense.

Particular emphasis is laid upon the unique mounting of the tracks 6 for permitting necessary adjustments thereof, upon the combined connection between the two sets of tracks and the hanger bars 14, upon the offset arrangement of the outer rollers of carriage 20 to prevent binding of said rollers, and in fact upon the general structure and arrangement of parts shown and described. This assemblage of parts has proven highly satisfactory and therefore constitutes the preferred form of the invention but it is to be understood that within the scope of the appended claims, numerous changes may be made without sacrificing the principal advantages.

I claim:

1. A ditch filling machine comprising a portable frame having a pair of transverse sleepers secured to its upper side, vertical plates secured to opposed sides of said sleepers and extending below the same, bearing blocks secured between the lower ends of said plates and having vertical openings, vertical hanger bars slidable in said openings and through similar openings in the sleepers, said hanger bars having vertically

spaced openings in their upper ends, pins inserted through said openings and resting on the sleepers to hold said hanger bars in vertically adjusted position, a pair of relatively fixed horizontal tracks extending beneath the frame and supported pivotally at one end, the other end of said tracks being disposed adjacent the lower end of said hanger bars, a pair of relatively movable tracks alined with the last named ends of the fixed tracks, means hingedly connecting the adjacent ends of the two pairs of tracks and at the same time pivotally connecting said tracks with the lower ends of said hanger bars, a carriage having rollers to travel from either pair of tracks onto the other, an earth scraper carried by said carriage, means for moving said carriage in either direction, and means for adjusting the outer end of the movable tracks vertically.

2. A ditch filling machine comprising a portable frame having a pair of transverse sleepers, vertical plates secured to opposite sides of said sleepers and extending below the same, bearing blocks secured between the lower ends of said plates and having vertical openings, vertical hanger bars slidable in said openings and through similar openings in the sleepers, means for holding said hanger bars in vertically adjusted position, a pair of relatively fixed horizontal tracks extending beneath the frame and supported pivotally at one end, the other end of said tracks being disposed adjacent the lower end of said hanger bars, a pair of relatively movable tracks alined with the last named ends of the fixed tracks, means hingedly connecting the adjacent ends of the two pairs of tracks with the lower ends of said hanger bars, a carriage mounted on said tracks and carrying an earth scraper, and means for adjusting the outer ends of the movable tracks vertically.

In testimony whereof I have hereunto set my hand in the presence of two subscribing witnesses.

HARLAND W. CARDWELL.
